CATHODE RAY TUBE

Hans Boersch, Berlin-Charlottenburg, Germany,
assignor to General Electric Company, a corporation of New York

Application August 23, 1940, Serial No. 353,949
In Germany September 12, 1939

5 Claims. (Cl. 315—14)

The present invention relates to a cathode ray tube useful for investigating objects by electron optical means.

In a cathode ray device such as an electron microscope in which a visible image is formed by the action of an electron stream, it often happens that the image produced is of blurred character, this blurring being due at least in part to the fact that the various components of the electron stream are of different velocities. Thus, in electron microscopes of the type in which the image is produced by projecting an electron stream through the object under investigation, electrons which are slowed down in passing through the object fail to follow the same paths as the electrons of higher velocity and consequently produce blurring of the image. A similar effect may be noted if the primary electron source is itself of such character as to give rise to electrons of varying velocities.

According to the present invention the difficulties described in the foregoing are minimized by providing in proximity to the image-reproducing surface a braking electrode, preferably in the form of a foil or grating, for preventing slowly moving electrons from reaching the surface. It is found that in the use of the invention in an electron microscope the shadow of the grating which is produced on the image surface has little effect in obscuring the greatly magnified image of the object under investigation.

The features which I desire to protect herein are pointed out with particularity in the appended claims. The invention itself may best be understood by reference to the following description taken in connection with the drawing in which Fig. 1 shows schematically an elementary form of electron microscope embodying the invention and Figs. 2 and 3 respectively indicate modifications of the invention.

Referring particularly to Fig. 1, there is shown in dotted outline a sealed evacuated envelope 1 which is assumed to enclose the operative parts of an electron microscope. These include a cathode 2, which may be regarded as the source of an electron stream and a generally tubular accelerating anode 3 which is maintained at high potential by means of a voltage source 6 and which serves to direct the electrons along a desired course. A magnetic electron lens, provided, for example, by means of a coil 4, serves to focus the electron stream to a small cross-section at the point where it enters the anode 3 through a small opening 5 provided in the end wall of the

anode. The object to be investigated is positioned as indicated at 7 in proximity to the anode opening 5 and is arranged to be traversed by the electron stream. It is assumed that the object 7 is at least partially of electron-permeable character and that it represents some element, such as a minute organism, which is desired to be viewed as an enlarged reproduction of the same.

10 It will be understood that with the arrangement specified above, the electron stream, after passing through the object 7, will possess a cross-sectional pattern which is representative of the character of the object under investigation.

15 Moreover, assuming that the stream is of sharply divergent character it may be made to project an enlarged image or shadow of the object on a suitable reproducing surface. Such a surface, which may take the form of a fluorescent screen or a photographic film, is positioned in the path of the stream as indicated at 10.

20 Between the image-reproducing surface 10 and the extremity of the anode 3 there is provided a braking electrode, which is preferably in the form of a grating as indicated at 11. (The diameter of the wire elements of the grating is greatly exaggerated in the drawing for the sake of clarity). In order that this electrode may 25 perform its desired function it is preferably maintained at a low potential, on the order of a cathode potential so that it tends to eliminate from the electron stream all electrons which are 30 of such low velocity as to have a tendency to produce objectionable blurring of the image reproduced on the surface 10. Due to the fact that the braking electrode is in close proximity to the surface 10 the shadow which it casts on the surface does not obscure the object image to an 35 objectionable degree.

40 It is desirable to assure the presence of a reasonably uniform field between the electrode 11 and the extremity of the anode 3. To facilitate this result one may provide a further grating, indicated at 12, as an electron-permeable diaphragm across the end of the anode 3. This 45 grating is maintained at the same potential as the anode.

40 As an alternative means for improving the field distribution between the braking electrode 50 and the extremity of the tubular anode, one may make the braking electrode of curvi-linear superficial form as indicated in the alternative modification of Fig. 2. Since the various elements of this figure correspond in function to the similar 55 elements described in connection with Fig. 1,

they are identically numbered except for the expedient of priming the various index numerals.

A still further variation which may prove useful in certain cases is shown in Fig. 3. In this case the braking electrode comprises a pair of gratings 13 and 14 which are successively arranged and which are maintained at a common potential. The space between the gratings may be closed up laterally as by the provision of a circularly extending conducting wall as indicated at 15. In the use of a pair of gratings as indicated in Fig. 3 it is preferable to mount the gratings in such fashion that their wires cross perpendicularly so that the projection of the two gratings represents a screen or grid.

The use of a braking electrode in the manner specified in the foregoing requires certain precautions in order to prevent the accumulation of charges on the image-reproducing surface. Normally the reproducing surface does not accumulate charges because secondary electrons liberated from it fly to the high voltage anode and thus help to maintain the surface in discharged condition. The presence of the braking electrode, however, tends to lessen this effect so that provision should be made for imparting transverse conductivity to the image reproducing surface as, for example, by giving it a metal coating.

The invention described herein may be used to advantage in investigating thick objects which have previously been found impossible of investigation by electron optical means because of the blurring effects initially referred to. Numerous additional modifications may obviously be made in the invention and I aim in the appended claims to cover all such equivalent variations as come within the true spirit and scope of the foregoing disclosure.

What I claim as new and desire to secure by Letters Patent of the United States, is:

1. A cathode ray tube for investigating objects by electron optical methods comprising means including an electron lens system for producing an electron stream having a cross-sectional pattern representative of the particular object under investigation, a surface adapted to be affected by the electrons in the said stream to produce a visible image corresponding to the cross-sectional pattern of the stream, an electron-pervious electrode lying in a surface having a substantial component perpendicular to the direction of travel of the electrons and interposed between the electron lens system and the said surface and in proximity to the latter, and means for applying a braking potential to the said electrode so as to prevent slow electrons in the stream from reaching the surface.

2. A cathode ray tube for investigating objects by electron optical methods comprising means including an electron lens system for producing an electron stream having a cross-sectional pattern representative of the particular object under investigation, a surface adapted to be affected by the stream to produce a visible image corresponding to the cross-sectional pattern of the stream, an electron-pervious electrode in the form of a

5 conductive grating interposed between the said electron lens system and the said surface and in proximity to the latter; and means for applying a braking potential to the said electrode so as to prevent slow electrons in the stream from reaching the surface.

3. A cathode ray tube for investigating objects by electron optical methods comprising means for producing an electron stream having a cross-sectional pattern representative of the particular object under investigation, a generally tubular

20 electrode arranged to be traversed by the said stream for accelerating and directing the same, an image-reproducing surface adapted to be affected by the stream after its traversal of the said electrode, and an electron-pervious braking electrode extending across the path of the electron stream in a region between the said tubular electrode and the said image-reproducing surface for preventing slow electrons in the stream from reaching the surface, the said braking electrode being of curvilinear contour in planes taken parallel to the path of the electron stream.

4. A cathode ray tube for investigating objects by electron optical methods comprising means for

35 producing an electron stream having a cross-sectional pattern corresponding to the particular object under investigation, a tubular electrode arranged to be traversed by the stream and serving to accelerate and direct the same, an image-reproducing surface adapted to be affected by the stream after its passage through the said tubular electrode, an electron-pervious braking electrode interposed between the said tubular electrode and the image-reproducing surface for preventing slow electrons in the stream from reaching the said surface and electron pervious conductive means of planar character mounted across the end of the tubular electrode which is adjacent to the braking electrode for producing a uniform field distribution between such electrodes.

45 5. A cathode ray tube according to claim 1 characterized by the fact that the electron-pervious electrode comprises a pair of successively arranged conductive gratings which are maintained at a common potential.

HANS BOERSCH.
